UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,880, dated March 11, 1884.

Application filed January 28, 1884. Term of patent 3½ years.

To all whom it may concern:

Be it known that I, W. L. JACOBS, of East Orange, in the State of New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The feature of the design is the general ef-

fect produced by the groundwork, which consists of right-lined shadow-figures regularly arranged over the face of the design, as clearly shown in the photograph. Above this ground are irregularly scattered large conventional figures, without connection or special relation to one another or to the groundwork.

I claim—

The design for a carpet, substantially as shown and described.

W. L. JACOBS.
